UNITED STATES PATENT OFFICE.

HUGH P. CHRISTENSEN, OF DES MOINES, IOWA, ASSIGNOR TO H. P. CHRISTENSEN COMPANY, INC., OF KIMBALL, SOUTH DAKOTA, A CORPORATION OF SOUTH DAKOTA.

EXERCISER, REDUCER, AND HEALTH BUILDER.

Application filed March 10, 1928. Serial No. 260,725.

The object of my invention is to provide an exerciser, reducer and health builder of very simple and durable construction.

More particularly, it is my object to provide such an exerciser so constructed and arranged as to be peculiarly adapted for taking a great variety of exercises.

Another purpose of my invention is to provide an exerciser comprising a pair of 10 stirrups adjustably connected together with a pair of handles and adjustable tension devices arranged between the stirrups and the handles.

In this connection, it is my purpose to 15 provide stirrups of peculiar and novel construction.

With these and other objects in view, my invention consists in the construction, arrangement and combination of the various 20 parts of my exerciser, reducer and health builder, whereby the objects contemplated are attained, as hereinafter more fully set forth, pointed out in my claims, and illustrated in the accompanying drawings, in 25 which:

Figure 1 shows a perspective view of an exerciser embodying my invention.

Figure 2 is an enlarged, detail, sectional view taken on the line 2—2 of Figure 1; and

Figure 3 is a side elevation illustrating 30 the manner of using my exerciser.

In the drawings herewith, I have used the reference numeral 10 to indicate generally the stirrup forming a part of my exerciser. 35 I use two of these stirrups, each having at its upper part a loop 12 and at its inner side a loop 14.

The stirrups 10 are connected by means 40 of a flexible strap 16, the ends of which are fastened by a buckle 18, so that the maximum distance between the stirrups may be varied by adjusting the strap 16.

I provide for my exerciser a pair of 45 handles. The handles are indicated generally at A. Each handle comprises a U-shaped member 20, having at its lower end a loop 22 and at its upper end a rotatable handle member 24 received between the upper ends of the arms of the yoke 20 and 50 mounted on a spindle or the like 26.

Between each stirrup loop 12 and the loop 22 of the corresponding handle is a flexible,

resilient strap or the like 28 made of a strip of strong rubber.

55

The ends of each rubber member 28 are connected by means of a buckle or the like 30, comprising a substantially, rectangular frame, longer than it is wide, and having a central cross bar 32 arranged a little above 60 the plane in which the frame of the buckle lies, as illustrated in Figure 2.

Thus there is provided in this exerciser a pair of stirrups 10 connected together by means of a strap 16 of non-resilient material, so that the maximum distance of operation 65 of the stirrups can be regulated.

Each stirrup is connected with a handle A by means of a strong rubber connecting member, the length of which can be varied 70 as may be desired.

Such an exerciser is capable of a great variety of uses.

One manner of using the exerciser is illustrated in Figure 3. The user 34 puts his 75 feet through the stirrups 10, grasps the handle, and sits down on the floor, and by lying down can stretch the members 28 and then by rising to sitting posture while the members are thus under tension can exercise 80 the leg, arm, abdominal, back and neck muscles.

There is thus possible, an exercise similar 85 to that of rowing a boat, with the consequent exercising and strengthening of the muscles as explained.

The user may lie flat on his back, raise his legs to position extending upwardly, and then swing them down to prone position for another exercise, or if he desires the user 90 may stand on the floor and bend forwardly and straighten up for a very effective exercise.

The strap 16 may be taken off for using 95 one of the exerciser devices, gripping the stirrup with one hand and the handle with the other.

These are simply illustrative exercises, and it may be seen that any number of different exercises may be practiced with my 100 device.

I claim as my invention:

1. In a device of the class described, a pair of stirrups, each having a loop at its upper side and a loop at its inner side, a 105 longitudinally adjustable flexible member

connecting the inner loops, handles comprising yokes, with rotatable handle elements between their arms and with loops at their portions opposite the rotatable handles, and 5 flexible, resilient, longitudinally, extensible members connecting the respective loops on the upper sides of the stirrups with the loops on the handles.

2. In a device of the class described, a pair of stirrups, a longitudinally adjustable 10 flexible member connecting the stirrups, handles, and flexible, resilient, longitudinally extensible members connecting the stirrups with the handles.

Des Moines, Iowa, March 5, 1928.

HUGH P. CHRISTESEN.
